UNITED STATES PATENT OFFICE.

WILLIAM H. HILL, OF ELYRIA, OHIO.

DESIGN FOR A HEATING STOVE.

Application filed October 10, 1923. Serial No. 7,462. Term of patent 14 years.

To all whom it may concern:

Be it known that I, WILLIAM H. HILL, a citizen of the United States, residing at Elyria, in the county of Lorain and State of Ohio, have invented a new, original, and ornamental design for a Heating Stove, of which the following is a specification, reference being had to the accompanying drawing, forming part thereof:

In said drawing—

The figure is a perspective view showing a heating stove embodying my new design;

I claim:

The ornamental design for a heating stove, as shown.

In witness whereof, I have hereunto subscribed my name.

WILLIAM H. HILL.
